UNITED STATES PATENT OFFICE.

FRANK WOJCIECHOWSKI, OF STAUNTON, ILLINOIS.

DESIGN FOR A POCKET CIGAR-HOLDER.

56,112.

Specification for Design.

Patented Aug. 17, 1920.

Application filed March 10, 1920. Serial No. 364,751. Term of patent 7 years.

To all whom it may concern:

Be it known that I, FRANK WOJCIECHOWSKI, a citizen of the United States of America, residing at Staunton, in the county of Macoupin and State of Illinois, have invented a new, original, and ornamental Design for a Pocket Cigar-Holder, of which the following is a specification, reference being had to the accompanying drawing, forming part thereof.

The figure is a view in perspective of a pocket cigar holder, showing my new design.

I claim:—

The ornamental design for a pocket cigar holder, as shown.

FRANK WOJCIECHOWSKI.
